INVENTOR:

John F. Mascher

UNITED STATES PATENT OFFICE.

JNO. F. MASCHER, OF PHILADELPHIA, PENNSYLVANIA.

ALARM-CLOCK.

Specification of Letters Patent No. 22,883, dated February 8, 1859.

To all whom it may concern:

Be it known that I, JOHN F. MASCHER, of the city of Philadelphia and State of Pennsylvania, have invented a new and useful 5 Improvement in Clocks, Whereby They May be Made to Strike at any Desired Interval of Time; and I do hereby declare that the following is a full, clear, and exact description of the same, reference being had 10 to the annexed drawings, making a part of this specification, in which—

Figure 1, is a front view of my improved clock. Fig. 2, is a side view of the same. Fig. 3, is a front view of the several parts 15 added to an ordinary clock by me.

My invention consists in applying a ratchet or other shaped pinion or wheel A to the arbor of one of the wheels of the going part of a clock as herein shown to the 20 arbor of the third wheel, one pivot of said arbor having its bearing in a slotted shaped hole B, in the frame; said pinion A meshing into the rack C having its center of motion at D.

25 A spring E secured to the clock frame is used for the purpose of throwing the rack back against the snail F whenever the pinion A is disengaged from the teeth of the rack C, by means of the lever G, and through the instrumentality of the striking 30 part of the clock, one end of said lever being pressed aside by each pin in the pin or strike wheel K, of the clock as said wheel rotates, the other end of the lever lifting 35 the arbor of wheel A out of place by means of the motion imparted to the lever by the pin wheel of the striking part of the clock.

The rack C is used in part for the purpose of unlocking the striking part of the 40 clock, through the instrumentality of a detent lever H, and it also in conjunction with the pinion A and snail F serves to divide the hour or any portion of time into minutes, and if required half or quarter minutes, a spring I secured to the frame serves

to keep the pitching of the pinion A and rack C engaged during such times that the clock is not striking.

The brass hand J is secured to the sleeve of the snail and is used to change the time 50 of striking, the figures upon an ordinary clock dial serving as an index for that purpose, the hub of the snail is a tube, fitting spring tight upon a tube securely fastened to the frame, the axis of the snail, minute and hour hands of the clocks are concentric, as the hand J is moved from one figure upon the dial to the other a corresponding "step" of the snail is presented to the leg of the rack, the highest step in this case 60 corresponds to one minute and the lowest to ten minutes, but I prefer twenty-four steps or divisions upon the snail to correspond with from one-half to twelve minutes so that the clock is capable to strike either one 65 or twenty-four times per twelve minutes.

The rack in the case under consideration unlocks the striking part by direct action, but in some cases it may be desirable to do that duty by recoil action.

70 The clock so constructed is designed to be used for the purpose of timing and starting passenger railroad cars, omnibuses, and other vehicles, which require to be started at regular and irregular intervals of time, 75 and also for timing the exposure of daguerreotype and other photographic pictures, &c.

I do not claim either the rack, pinion or snail separately, but

70 I claim—

The application of the rack pinion and snail in the manner set forth to the going part of a clock or watch for the use and purpose described.

JOHN F. MASCHER.
